(57) **CLAIM**

The ornamental design for a drill press, as shown and described.

DESCRIPTION

FIG. 1 is a side view of the drill press, showing our new design;

FIG. 2 is a side view showing the side opposite that shown in FIG. 1;

FIG. 3 is a back view;

FIG. 4 is a front view;

FIG. 5 is a top view; and,

FIG. 6 is a bottom view.

The hub and handles shown in broken lines illustrate an alternative configuration, with the hub and handles situated on the opposite side of the drill press.
